Design for the Doors and Panels of Stoves.
No. 1,187. By N. S. Vodder, of Troy, N. Y.
Assignor to Potter & Co., of the same place.

Witnesses,
George Macarolle
Aldrin F. Park.

Designor,
N. S. Vodder

Patented Jan'y 3. 1860.

Des. 1187

N. S. Wedder, of Troy, N.Y.
Assignor to Potter & Co. of same place,
Letters Patent No. 1187. Dated Jan 9, 1860.

The schedule referred to in these Letters Patent and making part of the same.

To all whom it may concern:

Do it known that I, N. S. Wedder, of the City of Troy, in the
County of Rensselaer, and State of New York, have invented or produced a new and
original design for the Doors and Panels of Cooking Stoves; and I do hereby declare

Dec. 1187

2
that the following is a full and exact description of the same, reference being had to the annexed photographic drawing making a part of this specification.

My said design consists of a compound ornament, composed of the representation of a rectangular parchment, *m*, with its middle part drawn over a convex surface, *n*, and held down by a ring, *p*, around it, and with its corners twisted into tapering spirals, *q*, and the intermediate parts rolled into scrolls, *r*, and pierced by the stems of three-lobed leaves, *s*, this being all formed and disposed upon the central portion of the check-work ground, *t*, as shown in the annexed drawing.

What I claim as my invention or production and desire to secure by Letters Patent is the ornamental design herein described and represented in the annexed photographic drawing for the doors and panels of stoves.
